JAR WRENCH

Charles Ira Brown, 727 Ridge Road, Smoke Rise,
Kinnelon, Butler P.O., N.J. 07405

Filed Jan. 11, 1967, Ser. No. 6,137

Term of patent 14 years

(Cl. D.44—29)

Fig. 1.

Fig. 2.

Fig. 3.

Fig. 4.

Fig. 5.

*Fig. 6.**Fig. 7.**Fig. 8.**Fig. 9.**Fig. 11.**Fig. 10.*FIG. 1 is a top plan view of a jar wrench showing my new design;

FIG. 2 is a side elevational view;

FIG. 3 is a bottom plan view;

FIG. 4 is a right end elevational view;

FIG. 5 is a left end elevational view;

FIG. 6 is a top plan view of a jar wrench showing another form of my new design;

FIG. 7 is a side elevational view;

FIG. 8 is a bottom plan view;

FIG. 9 is a right end elevational view;

FIG. 10 is a left end elevational view; and

FIG. 11 is an enlarged fragmentary perspective view of the upper arm member shown in FIG. 10.

This is a continuation-in-part of my earlier filed application Ser. No. D.291 of Dec. 22, 1965, now abandoned.

I claim:

The ornamental design for a jar wrench, as shown and described.
